UNITED STATES PATENT OFFICE.

JAMES H. MONINGER, OF COLUMBUS, OHIO.

VEHICLE.

SPECIFICATION forming part of Letters Patent No. 678,015, dated July 9, 1901.

Application filed February 14, 1901. Serial No. 47,282. (No model.)

To all whom it may concern:

Be it known that I, JAMES H. MONINGER, a citizen of the United States, residing at Columbus, in the county of Franklin and State 5 of Ohio, have invented a certain new and useful Improvement in Vehicles, of which the following is a specification.

My invention relates to the improvement of vehicles; and the objects of my invention 10 are to provide an improved closed-top construction adapted for use on the body of an ordinary piano-box buggy, to provide means whereby said closed top may be applied to bodies of different dimensions, and to produce other improvements, the details of construction of which will be more fully pointed out hereinafter. These objects I accomplish 15 in the manner illustrated in the accompanying drawings, in which—

20 Figure 1 is a side elevation of a piano-box buggy-body, showing my improved top thereon. Fig. 2 is a front elevation of the same. Fig. 3 is a sectional view on line xx of Fig. 2. Fig. 4 is a sectional view on line yy of Fig. 25 Fig. 1. Fig. 5 is a detail view in perspective showing the inner portion of one end of the buggy-body with parts of my improved top connected therewith. Fig. 6 is a similar view showing the interior of a portion of the buggy- 30 body, a portion of the seat-frame, and a part of my improved top; and Fig. 7 is a detail view in perspective of one of the top frame and body uniting brackets which I employ in the manner hereinafter described.

35 Similar numerals refer to similar parts throughout the several views.

In carrying out my invention I remove from an ordinary piano-box body 1 the seat which ordinarily rests upon the side projections 1^a, 40 the usual dash of the open vehicle likewise being removed. The substantially-closed top which I employ on the open-vehicle body consists in a top-body, of which 2 represents the sides and 3 the seat sides.

45 4 represent front corner-standards which are supported from each side of the forward end of the body 1 in the manner hereinafter described.

50 As indicated in the drawings, a door-space 5 is formed on each side of the vehicle between each of the forward frame-standards 4 and the forward portion of the body sides

2. As shown more clearly in Fig. 6 of the drawings, the top sides 2 and top-back 2^a are supported from the usual open-body seat-frame comprising the front and rear transverse seat-frame bars 6 and inner side-bars 7, the base and inner side portion of each of the top sides 2 being provided with inwardly-projecting sills or bars 8, which, as indicated 55 at 9, are bolted to the seat-frame bars 6 of the body. Upon the front and rear seat-frame bars 6 are secured frame-bars 10, to the ends of which are bolted or otherwise secured, as indicated at 11 in Fig. 6, the inner frame-standards 12 at the forward end portions of the top sides 2. As shown in the drawings, the outer face of each of these inner frame-standards is preferably provided with a groove 12, extending throughout the greater portion 70 of its length.

In forming the connection of the forward portion of the top-body with the body 1 I employ a forward top-frame, of which 14 represents a lower horizontal frame-bar, which 75 rests upon the upper side of the vertical forward wall 1^b of the body 1. (See Figs. 5 and 3.) This frame-bar 14, which is of sufficient width to form an inwardly-extending flange at the top of the body portion 1^b, has formed 80 therein near each end a longitudinal slotted opening 15, and from the ends of this frame-bar 14 rise the forward corner frame-standards 4 of the top-body, the inner faces of standards 4 being provided with grooves 4^a, which are opposite and correspond with the grooves 13 of the top-frame standards 12. At the junction of the sides and forward end of the body 1 I provide vertical corner-posts 16, and to the inner face of each of said corner-posts I secure the 90 vertical downwardly-extending arm 17^a of a top frame and body uniting bracket 17. This bracket, as indicated more clearly in Fig. 7 of the drawings, consists in an angular shank portion comprising said arm 17^a and an upper 95 outwardly-extending arm 17^b, which terminates in an upwardly-extending threaded stem or bolt 17^c. The portion 17^b bears in the recessed upper end of the corner-post 16, while the bolt portion 17^c extends upward 100 loosely through the corresponding slotted opening 15 of the cross frame-piece 14, said bolt portion being adapted to receive a nut 18. 19 represents the vertical dash, which is se-

- cured at its ends to the top-frame standards 4 and which rises from the front of the frame-bar 14. Above the dash the frame-standards 4 have secured thereto suitable inner frame-
5 pieces 20, within which and between the dash and the upper transverse top-frame bar 21 is fitted a suitable window-frame 22, the upper side of the latter being hinged, as indicated at 23, to said upper transverse frame-bar 21.
10 This window-frame is provided with a plate-glass filling, such as is indicated at 22^a, and when said frame is swung upward is adapted to have its lower end detachably engage a pivoted depending hook 24, which is on the
15 underside of the vehicle-top roof or roof-ceiling. It is obvious that both the sides and back of the top-body may be provided with suitable windows, such as are indicated at 25 and 26.
20 The grooves 13 and 4^a of the top-frame standards 12 and 4 are adapted to receive and form guides for the edges of curtains 27, which are mounted on suitable rollers 28, journaled above the doorways 5. It is obvious, however, that the doorways 5 might be provided with swinging or sliding doors, if desired.
25 Owing to the fact that the bolt portions 17^c of the brackets 17 project through slotted
30 openings 15 of the frame-bar 14 it is obvious

that the top-frame may be applied to bodies of different widths, thus admitting of said top-frames being manufactured of a standard size and adapted for use on bodies of varying widths.

35

From the construction which I have herein shown and described it will be seen that a simple and desirable construction of closed-vehicle top is provided, through the employment of which an ordinary piano-box buggy-
40 body may be readily converted into a closed-top vehicle, such as is adapted for the winter months, and that said closed top may when desired be removed and the open body provided with the usual seat and dash.

45

Having now fully described my invention, what I claim, and desire to secure by Letters Patent, is—

In a vehicle, the combination with an open piano-box buggy-body, of a separately-formed top and top frame comprising connected top-frame standards and a forward cross frame-piece 14 and means for adjustably uniting said top with said body, substantially as specified.

50
JAMES H. MONINGER.
